UNITED STATES PATENT OFFICE.

JAMES HUDSON, OF NEWTOWN, INDIANA.

DEVICE FOR PLASTERING.

SPECIFICATION forming part of Letters Patent No. 422,528, dated March 4, 1890.

Application filed December 9, 1889. Serial No. 333,068. (No model.)

To all whom it may concern:

Be it known that I, JAMES HUDSON, of New-
town, in the county of Fountain and State of
Indiana, have invented certain new and use-
ful Improvements in Devices for Plastering,
of which the following is a specification, ref-
erence being had to the accompanying draw-
ings, and to the letters of reference marked
thereon.

5 To My invention is intended to provide means
whereby a coat of plaster can be laid on a se-
ries of laths, a brick or other wall, or other
vertical surface, in a perfectly smooth, flat,
and level state, and of even thickness, neat-
ness of finish and economy in the use of
15 plaster being thus obtained and time and
labor saved.

In the accompanying drawings, Figure 1 is
a perspective view of my improvement; Fig.
20 2, a side view, and Fig. 3 a cross-section on
the line $\alpha\alpha$ of Fig. 2.

Similar letters of reference indicate similar
parts in the respective figures.

A represents a rod, which in cross-section
25 is preferably of the shape shown in Fig. 3.
The upper end of the rod is shaped as shown
in Figs. 1 and 2—that is to say, the end is
provided with a projection or hook *a*, beveled
or inclined on the top and flat underneath. The
30 hook connects with the rod *A* at a T-shaped
formation *b*. The rod is preferably made of
steel, its back being true. In carrying out
my invention two of such rods are used, of
such a length as to extend up the wall to be
35 plastered to a height conveniently reached by
the plasterer.

In operation the plasterer first coats the
rod *A* as high as he can conveniently reach.
He then hooks the rods *A* over the laths a
40 certain distance apart. The hook *a* of each
rod enters and becomes embedded in the plas-
ter, the hold thus given aiding in steadyng
the rod. At the same time the whole length
of the rod is embedded in the plaster, which
45 keeps it in a vertical position and prevents
swinging movement. The inner face of the
T-shaped formation *b* presses against the
outer surface of the lath to which the rod is
hung, and by increasing the bearing-surface
50 has the effect of preventing the twisting of
the rod. The wedge-shaped cross-sectional

formation of the rod serves to cause it, in be-
ing pressed into the plaster and up against
the laths, to turn, crowd away, or clear the
gravel or other extraneous matter, and thus
55 to readily reach its proper vertical posi-
tion. Two rods being thus embedded and
anchored in the plaster and suspended from
the laths, a straight-edge of a length greater
60 than the distance apart of the rods is moved
or scraped over their back surfaces, which, as
they project a uniform distance out from the
face of the laths, causes the layer of plaster
65 to be made of equal thickness throughout,
and at the same time gives a perfectly level
and smooth finish. Great saving in the use
of plaster is thus effected and a superior job
of work accomplished at a saving of time and
labor.

Each end of the rod may be provided with
70 a projection or hook *a*, if desired; and my in-
vention is intended to apply to a rod, whether
one or both of its ends are constructed as
shown in Figs. 1 and 2.

If my invention is used for plastering a
75 brick or other wall having lines of mortar,
the hooked end is driven into the mortar, its
back and that of the T-shaped formation *b*
serving as a poll to receive the blows of the
80 hammer.

The invention is applicable to brick, lathed,
dry scratch-coat, and other descriptions of
walls requiring a layer of plaster.

If desired, one or more additional T-shaped
85 formations *b* may be attached to the rod to
aid, by fitting up against the laths, in keeping
it from twisting; or the formation may be X-
shaped, as shown in Fig. 1, to give greater
bearing-surface.

It will be understood that the layer of plas-
90 ter having been leveled, smoothed, or scraped
by means of the straight-edge, one of the rods
is to be shifted with reference to the other,
and so on until the whole area to be plastered
has been gone over.

95 I claim as my invention—

1. A device for gaging a layer of plaster
upon a wall, (the same to be used as one of a
pair,) consisting of a metallic rod having a
wedge-shaped hook or projection *a* and a T
100 or X shaped formation or formations *b*, sub-
stantially as described.

2. A device for gaging a layer of plaster upon a wall, (the same to be used as one of a pair,) consisting of a metallic rod wedge-shaped in cross-section and having a projection adapted to enter between laths, brick, &c., and an enlarged part having a flat inner face, substantially as set forth.

In testimony whereof I have hereto set my hand and seal.

JAMES HUDSON. [L. S.]
